UNITED STATES PATENT OFFICE

159,129

FLOOR TYPE TILTING ARBOR SAW

James Andrews, Waterbury, Conn., assignor, by
mesne assignments, to Vickers Incorporated,
Waterbury Tool Division, Waterbury, Conn., a
corporation of Michigan

Application July 6, 1946, Serial No. 131,342

Term of patent 3½ years

(Cl. D93—3)

To all whom it may concern:

Be it known that I, James Andrews, a citizen of the United States of America, residing in Waterbury, county of New Haven, and State of Connecticut, have invented a new, original, and ornamental Design for a Floor Type Tilting Arbor Saw, of which the following is a specification, reference being had to the accompanying drawing, forming part thereof.

Fig. 1 is a side elevation of the floor type tilting arbor saw showing my new design.

Fig. 2 is a top plan view of the same.

Fig. 3 is a front elevation of the same.

Fig. 4 is a fragmentary sectional view on line 4—4 of Figure 1.

The other side, not shown, is substantially the same as the side shown with exception of the hand wheel and the rear, not shown, is substantially like the front shown and also has no hand

wheel. The characteristic features of the saw design disclosed reside in the base portions having the configuration and ornamentation shown.

I claim:

The ornamental design for a floor type tilting arbor saw, as shown and described.

JAMES ANDREWS.
